UNITED STATES PATENT OFFICE.

JOHN E. MITCHELL, OF ST. LOUIS, MISSOURI.

LIFT HOLDING AND DELIVERING DEVICE FOR HEEL-BUILDING MACHINES.

1,219,659.

Specification of Letters Patent. Patented Mar. 20, 1917.

Application filed March 25, 1916. Serial No. 86,662.

To all whom it may concern:

Be it known that I, JOHN E. MITCHELL, a citizen of the United States, residing in the city of St. Louis and State of Missouri, have invented new and useful Improvements in Lift Holding and Delivering Devices for Heel-Building Machines, of which the following is a specification.

This invention relates to the art of heel building, and has special reference to the construction, arrangement and operation of a plurality of magazines, each of which is adapted to contain a stack of lifts, with means for delivering simultaneously a lift from each magazine. One of the objects of the invention is to provide a series of magazines, each of which is open at its rear side, and is inclined in a direction away from the open side to permit of a stack of lifts being supported therein; a further object is to provide a series of magazines for lifts, each magazine having but one side wall, and the wall of each magazine after the first serving as a retaining wall for the lifts in the preceding magazine; a further object of the invention relates to the provision of means for simultaneously ejecting a bottom lift from each of the magazines; a further object relates to the provision of a plurality of magazines, each magazine comprising a single side wall, the lifts being retained between the side walls of adjacent magazines, and which magazines are adjustable vertically and horizontally; and a further object of the invention relates to an adjustable stop-plate for preventing displacement of the bottom lifts in the magazines on the return movement of the ejecting means. Other objects of the invention relate to details of construction and to combinations, arrangements, and operations of parts, all as hereinafter more fully set forth.

The invention is illustrated in the accompanying drawings, in which—

Figure 1 is a view in side elevation of a machine constructed according to my invention;

Fig. 2 is a plan view of the machine viewed in the direction of the arrow 2 of Fig. 1;

Fig. 3 is a view in front elevation viewed in the direction of the arrow 3 of Fig. 1; and

Fig. 4 is a sectional view on the line 4—4

of Fig. 2 and viewed in the direction of the 55 arrows.

Referring now to the drawings, the numerals 1, 2, indicate, respectively, two side frames which are provided about centrally of their upper side with rectangular depressions 3 which are adapted to receive the opposite end portions of a cross beam 4, the ends of which project beyond said side frames, as shown more clearly in Fig. 2. The said side frames are also provided with 60 open-sided recesses 5 at their top and forward side which receive a cross beam 6, the ends of which also project beyond the sides of the side frames, as shown more clearly in Figs. 2 and 3. Between the cross beams 4 and 6 I provide a table section 7, the upper side of which is flush with the upper side of the cross beams 4 and 6. At the rear of the cross beam 4 I also mount on the top of the side frames a table section 8, the upper side 70 of which is flush with the upper side of the cross beam 4, as shown more clearly in Fig. 4. The side frames 1 and 2 are preferably of cast iron and are secured to bolsters 9. The upper portion 10 of these side frames is 75 inclined forward or toward the operator, as indicated in Figs. 1 and 4, and the top of the machine, comprising the table sections 7 and 8, and the cross beams 4 and 6, are correspondingly inclined. Secured near opposite ends of the cross beam 4, respectively, are two standards 11, 12, between which extend two rods 13, 14, located, respectively, at the top and center of said standards, and having their opposite ends secured therein. 80 The numerals 15 indicate a series or bank of magazines, each of which, as shown by Fig. 2, is L-shaped in cross section, and affords a front wall 16 and a side wall 17. The front walls 16 of the magazines lie substantially in the same plane. Mounted on the front wall 16 of each magazine is a bracket member 18. Each of these bracket members is provided toward its opposite ends with a slot 19 through which extends a screw-threaded bolt 20 passing through the front wall 16 of the magazine. A binding nut 21 is mounted on the screw-threaded end of each of said bolts. Each of the brackets 18 is provided toward its upper end with a recessed seat 22, which is adapted to receive the rod 13. The numeral 23 indicates a 85 clamping plate which is loosely mounted on

a set screw 24 having screw-threaded engagement with the bracket 18 about centrally thereof. Said clamping plate has off-set ends 25 which are adapted to engage the respective rods 13 and 14, and, when the set screw 24 is turned home, it will draw the seat 22 of the bracket 18 into engagement with the rod 13 and the lower portion 26 of said bracket into engagement with the rod 14, whereby each of the magazines is supported on the rod 13 and is held in firm, fixed position by engagement of the bracket 18 with said rod and the rod 14. By loosening the binding nuts 21 the magazines 15 may be raised or lowered to remove their lower ends a greater or less distance from the table of the machine to provide a throat or passageway 27 for the passage of lifts under the magazines. The standards 11 and 12 and the magazines 15 supported thereby are perpendicularly disposed with reference to the top, or table, of the machine, and hence are inclined forward or toward the operator, as shown in the drawings. The side walls 17 of the respective magazines are parallel to each other, and, as clearly shown by Fig. 2, the several stacks of lifts 28 are retained between the side walls of adjacent magazines with their rounded ends resting against the front wall 16 of each magazine. In order to accommodate lifts of varying sizes I provide for a lateral adjustment of the magazines 15, and this is accomplished by simply loosening the binding screws 24 and sliding the magazines 15 over the rods 13 and 14 to the desired position, when the binding screws 24 are again turned home to clamp the magazines in the adjusted positions. By inclining the magazine 15 in a direction away from its rear open side, which, in the present machine, is in a direction toward the front of the machine, I am enabled to retain a stack of lifts in each magazine without the necessity of using a back wall. Were the magazines vertically disposed a back wall would be necessary, as otherwise there would be constant danger of a stack of lifts tilting backward and falling out of the magazine. The use of magazines having their rear side open so as to leave the edges of the lifts exposed possesses also a distinct advantage, in that the lifts may be inserted in the magazine by a lateral movement at any desired point in its height without the necessity of the operator having to reach to the top of the magazines for this purpose, which would be the case were the magazines inclosed on all sides. With the magazines supplied with lifts, it is one of the objects of my invention to provide for simultaneously ejecting the bottom lift from each of the magazines so that they can be pasted and assembled into a heel-blank with facility by the operator.

For this reason I eject the lifts so that they will rest on the fixed support or table at a point which is unobstructed by the magazines, that is at the side of the bank of magazines. To accomplish this object I 70 slidably mount on the table portion 8 at the rear of the machine an ejector plate 29, which is of a width to extend across all of the magazines and of a thickness to work in the space or throat 27 provided between 75 the lower ends of the magazines and the table or top of the machine. I also provide means for reciprocating the ejector plate 29 to eject the lifts by a movement which is lateral with respect to the direction in which the series of magazines extends. I find a convenient way to effect the reciprocation of the ejector plate to be as follows:

The ends of the said ejector plate are 85 extended beyond the top of the machine, and are apertured to receive the upper ends of throw-levers 30, the lower ends of which throw-levers are secured in crank arms 31 having hubs 32 mounted on opposite ends 90 of a shaft 33 and fixedly secured thereon as by means of set-screws 34. The shaft 33 is mounted in suitable bearings in the standards of the side frame members and fixedly secured at one end centrally of said 95 shaft is a foot lever 35 which projects forward beyond the machine so that its free end is within easy reach of the foot of the operator. The foot-lever 35 is normally held upward against a rod 36, acting as a 100 stop, by means of a coil spring 37, one end of which is secured to the foot-lever and the other end to a rod 38, extending between the frame members 1 and 2, and secured at its ends therein. A suitable stop 105 39 is preferably mounted on the front bolster 9 for limiting the downward movement of the foot-lever 35. It will be seen that when the foot-lever is depressed by the operator the throw-levers 30 will be moved 110 forward, carrying the ejector plate 29 under the magazines 15, the former engaging the straight breast-edges of the lifts and ejecting the lower lift in each of the magazines and moving them out upon the top or table 115 of the machine within easy reach of the operator. The pasting device need not be in the path of the lifts when ejected.

To build the heel-blank the lifts first have paste applied thereto and then are assembled in a suitable heel-forming device. I have shown in the drawings a pasting device comprising a receptacle 40 removably mounted at one end on a support 41 secured to the under side of the cross beam 6 and 120 at its other end on a beam 42 extending between the side frames 1 and 2 at the rear thereof. Mounted in bearings in the side frames of the machine is a shaft 43, one end of which is provided with a pulley 44, by 125 130

means of which it may be rotated. Secured on this shaft is a pasting roller 45 which is provided with annular circumferential recesses 46 through which extend two parallel bars 47 which are secured at opposite ends, respectively, to the cross beams 4 and 6. The roller 45 is constantly revolved by the pulley 44 and takes up the paste supplied to the receptacle 40. In practice the upper edges of the bars 47 are substantially flush with the periphery of the roller 45, and as the paste used is relatively thick, the layer of paste adhering to the roller will project slightly above the upper edges of said bars. In practice, therefore, when one of the lifts 28 is moved by the operator over the bars 47 its under side will be thoroughly and evenly supplied with paste by the roller 45. The particular pasting mechanism shown herein, and above briefly described, forms the subject-matter of a separate application for patent, (Ser. No. 86,663, filed March 25, 1916).

Secured centrally of the cross beam 6 is a suitable heel-blank former 48 which may be of any preferred construction, and, as indicated in Fig. 1, after the lifts have been drawn flatwise over the bars 47 and supplied with paste by the roller 45 they are raised on edge and pressed into the former 48. When a heel-blank of the desired height or thickness has thus been built up the heel-blank is removed and placed in a suitable press or holder until the paste is set. I have illustrated the heel-blank former 48 as a conventional means for enabling the lifts to be assembled. As a matter of fact, and as shown in a companion application (Ser. No. 86,614 filed March 25, 1916), I provide for moving the heel-former containing the heel-blank to a position opposite a holder of indeterminate length and forcing the successive heel-blanks into said holder. Such operation, however, forms no part of the present invention, and the heel-blank, after being assembled in the former 48, may be removed by hand and placed in a flat press, or otherwise treated, as above indicated.

As shown by Fig. 2, the lifts in the respective magazines successively increase in size, and as the four lifts are ejected from the bottom of the magazines in the manner above described the operator will build up the heel-blank by assembling the lifts in the order of their size, beginning with the smallest lift. The table operates as a support to hold the lifts stationary after they are ejected and guides the lifts when they are being assembled by hand. It will be understood, however, that all the lifts may be of the same size and that if necessary the magazines may be suitably adjusted laterally to accommodate varying sizes of lifts by loosening the set-screws 24 and

moving the magazines to the required position, as previously described.

In order to prevent the lowermost lifts from being carried backward and out of the magazines in the return movement of the ejector plate 29, I provide means independent of the ejector means, consisting of a bar 49 having its opposite ends 50 bent at right angles and provided each with a slot 51 by means of which the ends 50 are adjustably secured to the respective standards 11 and 12 by the use of set-screws 52. The bar 49 is located at the rear of the magazines 15 and extends across the same, as shown in Fig. 2, in close proximity to the rear sides thereof, preferably being angularly disposed or inclined relative to the rear side of the magazines, as shown by Fig. 4, so as to have its point of closest approach to the magazine opposite the throat 27, and thereby avoid the possibility of offering an obstruction to the downward movement of the lifts in the event one or more of them should project slightly beyond the others. It will be apparent, especially from an inspection of Fig. 4, that this bar rests on the ejector plate 29, and hence should the ejector plate 29 in its return movement tend to carry the lowermost lifts resting thereon backward with it, said lifts would engage the lower edge of the bar 49 and be prevented from such movement. In its return movement the forward edge of the ejector plate 29 is, as shown by Fig. 1, carried to, or slightly back of the bottom edge of the stop plate 49. By loosening the set-screws 52 the bar 49 may be adjusted toward or from the magazines according as the sizes of lifts used are varied. If the smallest size lift is materially smaller in size than the largest lift, it will also be apparent that the end of the bar 49 opposite the magazine containing the smallest lifts can be moved inward farther than the other end of said bar, so as to bring the first-named end of the bar substantially as close to the smaller lifts as the opposite end is to the largest lifts. In other words, the bar would then be given an inclined position to the magazines instead of extending parallel to the rear sides thereof as shown in Fig. 2.

I have shown only five magazines accommodating four stacks of lifts. It will be apparent, however, that a greater or less number of magazines may be used according to the height of the heel-blanks to be built. It will also be apparent that if the number of magazines in position on the machine is greater than the number of lifts required for a particular height of heel-blank being built, that lifts need only be supplied to the required number of magazines, and the remaining magazines be left empty. That is to say, the invention con-

templates simultaneously ejecting the lowermost lift from each of a plurality of magazines, whether such magazines be the total number of magazines employed or a less number.

In practice I find it decidedly advantageous, in stacking the lifts in the magazines, to insert the lifts in the magazines round side foremost. In this way a large number of lifts can be taken in the hand and inserted at one time, as the rounded sides of the lifts engaging the edges of the side walls of the magazine will direct the lifts into the magazine; whereas, should it be attempted to insert a number of lifts through the rear of the magazines with their flat or breast side foremost, one or the other of the corners of the lifts will invariably engage one or the other of the walls of the magazine and be turned sidewise, and this will result in distorting the position of other lifts held in the hand, so that it becomes impossible to insert the lifts in the magazine. Furthermore, when so positioned in the magazine the lifts will be discharged with their axes extending in the same direction, and with their rounded side toward the operator, who without changing their position, moves them over the pasting device and then raising the rounded end of each lift with his thumb, places it in the heel-former with its flat side resting upon the bottom members 93 thereof. Should the lifts be delivered flat side foremost and moved over the pasting device in that position, the operator could only with great difficulty lift the rear rounded side of the lift by the use of his fingers, besides being constantly liable to have his finger come in contact with the pasting roller.

I claim:

1. In a heel-building machine, the combination of a series of magazines for lifts, a table below said magazines and providing an uninterrupted exposed supporting surface on its upper side in front of said series of magazines, and means for simultaneously ejecting the lowermost lifts outwardly onto said table so that they will lie exposed and accessible thereon, said table operating as a guide and support for the lifts in assembling the same by hand.

2. In a heel-building machine, the combination of a series of magazines for lifts, a table below said magazines and providing an uninterrupted exposed supporting surface on its upper side in front of said magazines, a heel-former adjacent said table, and means for simultaneously ejecting the lowermost lifts of all of said magazines and at the same time moving the ejected lifts outwardly in front of said series of magazines onto said exposed upper surface of said table and toward said heel former, said table op-

erating as a guide and support for the lifts 65 in assembling the same by hand in said heel-former.

3. In a heel-building machine, the combination of a fixed supporting table having an exposed upper face, a series of magazines 70 for lifts supported thereabove, said magazines having their lower ends open and disposed adjacent the face of said table, each of said magazines having an opening on its rear side permitting the feeding of lifts 75 into each magazine by a lateral substantially horizontal movement said magazines being inclined in a direction away from their open sides, and means for simultaneously ejecting the lowermost lift from 80 each of said magazines by moving each lowermost lift in the direction away from the open side of its magazine, and out onto the exposed face of said table, said table operating as a rest to hold the ejected lifts 85 stationary to enable the operator to seize the lifts and assemble the same by hand.

4. In a heel-building machine, the combination of a fixed supporting table having an exposed upper face, a series of magazines 90 for lifts supported thereabove, said magazines having the lower ends open and disposed adjacent the face of said table, each of said magazines having an opening on its rear side permitting the feeding of lifts 95 into each magazine by a lateral substantially horizontal movement, said magazines being inclined in a direction away from their open sides, means for simultaneously ejecting the lowermost lift from each of 100 said magazines by moving each lowermost lift in the direction away from the open side of its magazine, and out onto the exposed face of said table, said table operating as a rest to hold the ejected lifts 105 stationary to enable the operator to seize the lifts and assemble the same by hand, said magazines being individually adjustable longitudinally toward the face of said table, and means for securing said magazines in 110 any adjusted position.

5. In a heel-building machine, a support, a series of vertically-disposed magazines for lifts mounted thereon and having open lower ends spaced from the support, means for ejecting the lowermost lift from each of 115 said magazines, and means permitting of the independent adjustment of each of said magazines laterally with respect to the others.

6. In a heel-building machine, a support, a series of vertically-disposed magazines for lifts mounted thereon in juxtaposition to each other and having open lower ends spaced from said support, means permitting of the independent adjustment of each of 125 said magazines laterally with respect to the others, and means for simultaneously eject-

ing the lowermost lift from each of said magazines.

7. In a heel-building machine, an inclined support, a series of vertically-disposed magazines for lifts mounted in juxtaposition to each other on said support and having open lower ends spaced therefrom, each of said magazines being open on the side opposite to that toward which it is inclined,

means permitting of the independent adjustment of each of said magazines laterally with respect to the others, and means for simultaneously ejecting the lowermost lift from each of said magazines.

15 8. In a heel-building machine, the combination of a fixed support, a series of magazines for lifts mounted thereabove, each magazine having its lower end adjacent the said support and open on its rear side to enable the magazine to be replenished with lifts by inserting them through the open rear side of the magazine, and ejecting means for simultaneously ejecting the lowermost lifts from each of said magazines operating to leave the lifts lying exposed on the upper side of said support, and movable means resting on said ejector means for preventing the lowermost lifts from being moved out of the open sides of the magazines by said ejector means.

30 9. In a heel-building machine, a support, a heel-former adjacent said support, a series of magazines for lifts, each magazine having its lower end spaced from the support and having an open rear side leaving the rear edges of the lifts in each magazine exposed, means for simultaneously ejecting the lowermost lift from each of said magazines, and for advancing the ejected lifts to a position on said support between said magazines and said heel-former, and means common to all of said magazines for engaging the lowermost lift in each magazine to prevent the same from being moved out of the said open rear sides of the magazines.

45 10. In a heel-building machine, a support, a series of magazines for lifts mounted thereon, and having open lower ends spaced from the support, each of said magazines being open on its rear side to leave the edges of the lifts exposed, and permitting replenishing of the lifts through the open side, ejecting means for simultaneously ejecting the lowermost lift from each of said magazines onto said support, and a movable bar extending across all of said magazines at their rear in a position to prevent the lowermost lift in each magazine from being moved out of its open side, and resting by gravity on said ejecting means.

55 11. In a heel-building machine, a support, a series of magazines for lifts mounted thereon and having open lower ends spaced from the support, each of said magazines

having an open rear side, a bar extending across all of said magazines at their rear and positioned to prevent the lowermost lift in each magazine from being moved out of its open side, means permitting adjustment of said bar toward and from said magazines, and means for simultaneously ejecting the lowermost lift from each of said magazines.

65 12. In a heel-building machine, a support, a series of magazines for lifts mounted thereon and having open lower ends spaced from the support, each of said magazines having an open rear side, a bar extending across all of said magazines at their rear and positioned to prevent the lowermost lift in each magazine from being moved out of its open side, means permitting the independent adjustment of the opposite ends of said bar toward and from said magazines, and means for simultaneously ejecting the lowermost lift from each of said magazines.

75 13. In a heel-building machine, a support, a series of magazines for lifts mounted thereon and having open lower ends spaced from the support, each of said magazines having an open rear side, a bar extending across all of said magazines at their rear and being upwardly inclined in a direction away from the magazines, the lower edge of said bar being positioned to engage the lowermost lift in each magazine and prevent the movement of said lifts out of the open side of the magazines, and means for simultaneously ejecting the lowermost lift from each of said magazines.

80 14. In a heel-building machine, a support, a heel-blank former adjacent said support, a series of magazines for lifts having open lower ends spaced from the support, a plate slidably mounted on said support and extending across all of said magazines, and means for reciprocating said plate to cause it to pass under the lower ends of the magazines and to simultaneously eject the lowermost lift from each of said magazines and onto said support.

85 15. In a heel-building machine, a support, a heel-blank former adjacent said support, a series of magazines for lifts mounted above said support and having open lower ends spaced from the support, a plate slidably mounted on the support and extending across all of said magazines, a pair of throw-levers operatively connected with opposite ends of said plate, and means for actuating said throw-levers whereby to reciprocate said plate to cause it to pass under said magazines and simultaneously eject the lowermost lift from each of said magazines onto said support.

90 16. In a heel-building machine, a support, a heel-former adjacent said support, a series of magazines for lifts mounted above

- said support and having open lower ends spaced from the support, means for simultaneously ejecting the lowermost lift from each of said magazines onto said support, 5 and a pasting device mounted in said support out of the path of the lifts when ejected, but in proximity to the place of deposit of said lifts, to which the lifts may be applied by hand.
- 10 17. In a heel-building machine, a support, a series of magazines for lifts mounted thereon and having open lower ends spaced from the support, means for simultaneously ejecting the lowermost lift from each of 15 said magazines, an automatic pasting device mounted in said support out of the path of movement of the lifts when ejected, but in proximity to the place of deposit of said lifts, and a slideway extending from 20 the place of deposit of said lifts over and beyond said pasting device for supporting lifts passed by hand over the latter.
18. In a heel-building machine, a support, a series of vertically-disposed magazines 25 mounted thereon and having open lower ends spaced from the support, each magazine consisting of a side and a front wall, the side wall of each magazine serving as a retaining wall for the preceding magazine, 30 and means for successively ejecting the lowermost lift from each of said magazines.
19. In a heel-building machine, a support, a series of magazines for lifts mounted thereon and having open lower ends spaced 35 from the support, each of said magazines consisting of a side wall and a front wall, and being inclined in a direction toward the front wall, the side wall of each magazine serving as a retaining wall for the preceding magazine, and means for successively 40 ejecting the lowermost lift from each of said magazines.
20. In a heel-building machine, a support, a series of magazines for lifts mounted 45 thereon and having open lower ends spaced from the support, each of said magazines consisting of a side wall and a front wall and being inclined in a direction toward the front wall, the side wall of each magazine 50 serving as a retaining wall for the preceding magazine, means permitting the adjustment of each of said magazines laterally with respect to the other magazines, and means for successively ejecting the lower- 55 most lift from each of said magazines.
21. In a heel-building machine, in combination with a series of magazines open at their rear sides and having a front wall and each of said magazines being adapted 60 to receive a stack of lifts with their rounded sides resting upon the front wall of the magazine, means for simultaneously ejecting the lowermost lift from each of said magazines, a pasting device located in prox- imity to the place of deposit of said lifts 65 and adapted to apply paste to the lifts as the latter are successively moved over the same, and a heel-former positioned in line with said pasting device and having its bottom adapted to receive the flat or breast 70 side of the lifts.
22. In a heel-building machine, a supporting table having an exposed upper face, a bank of magazines for lifts, having their lower ends adjacent to said table, a heel-former adjacent said support, and means for simultaneously ejecting the lowermost lifts from each of said magazines onto the said exposed face of said table at a point 75 at the side of said bank of magazines. 80
23. In a heel-building machine, a supporting table having an exposed upper face, a bank of magazines operating to hold adjacent stacks of lifts with the rounded edges of said lifts disposed toward said supporting table, a heel-former adjacent said supporting-table, and means for ejecting the lowermost lifts of each of said magazines onto the said exposed face of said supporting table at the side of said bank of magazines. 85 90
24. In a heel-building machine, a supporting table, a series of magazines of progressively increasing width from one end of said series toward the other, said magazines being open on the same corresponding side to leave the edges of the lifts in the magazines exposed, and operating to hold stacks of lifts with the breast-edges of the lifts disposed toward the open sides of the magazines, means movable transversely to the direction in which said series of magazines extends, for engaging the breast-edges of the lowermost of said lifts in the magazines to eject the same simultaneously onto 95 100 said table with the axes of the ejected lifts extending in substantially the same direction, and a heel-former in which said lifts are to be assembled by hand in the same order in which the lifts lie on the table 105 after being ejected.
25. In a heel-building machine, the combination of a fixed table, a series of magazines, said magazines being of graduated size for holding lifts of gradually increased dimensions, means for simultaneously ejecting the lowermost lift from all of said magazines onto said table by a movement lateral with respect to the direction in which said series extends, and a heel-former adjacent said table, said table operating to hold the ejected lifts stationary to enable the same to be seized by the operator, and operating as a guide for assembling the lifts by hand in said heel-former in the same order in which the lifts lie on the table after being ejected. 115 120 125
26. In a heel-building machine, a fixed

support, a bank of magazines for lifts, means for ejecting the lowermost lift from each of said magazines onto said support so that the ejected lifts will lie at a point 5 on said support unobstructed by said magazines, a heel former adjacent to said support and a gluing device at said support

within reach of the operator whereby the ejected lifts may be glued and assembled by hand in said heel former.

In testimony whereof, I have hereunto set my hand.

JOHN E. MITCHELL.
